GAME BOARD

Donald Hickman, Chicago, Ill., assignor to Hifar Industries, Inc., Chicago, Ill., a corporation of Illinois

Filed Nov. 12, 1964, Ser. No. 82,552

Term of patent 14 years

(Cl. D34—5)

FIG. 1 is a top plan view of a game board embodying my new design;

FIG. 2 is a sectional view taken on line 2—2 of FIG. 1; and

FIG. 3 is an end view thereof.

I claim:

The ornamental design for a game board, substantially as shown.
